UNITED STATES PATENT OFFICE.

CRAWFORD C. LOOMIS, OF ILION, NEW YORK, ASSIGNOR TO REMINGTON ARMS COMPANY, INC., A CORPORATION OF DELAWARE.

FIREARM.

Application filed January 22, 1925. Serial No. 3,901.

This invention relates to firearms and for the purpose of illustration is shown as applied to the firearm of the "autoloading" type, such as the arm disclosed in Patent 5 659,507, Oct. 9, 1900, to J. M. Browning.

Guns of this type are adapted to contain a number of shells or cartridges in a magazine as well as a shell in the chamber. When the shell in the chamber is fired the recoil 10 of the arm is utilized for the purpose of setting in motion devices which open the breech, cock the hammer, eject the empty shell, transfer a fresh shell to the chamber, and close and lock the breech. The recoil 15 spring associated with the movable breech block serves in part, to absorb the energy of the recoil and to bring the actuated parts to rest in their rearmost position. However, in order to insure that the mechanism will 20 be fully operated at all times, it is necessary to so regulate the effect of the recoil spring that the rearwardly moving parts are moving with an appreciable velocity when they reach their rearmost position, and a positive stop must be provided to check their 25 movement. In the patent to Browning above identified, the rearwardly moving breech block and barrel extension are stopped by the engagement of the barrel extension with 30 the end of the receiver or frame. This arrangement is objectionable by reason of the fact that the contacting parts are both of metal, and the sharp blow which is struck against the stationary frame by the rearwardly moving members is unpleasant for 35 the shooter and injurious to both the frame and the mechanism. In some guns springs have been provided for stopping the rearward movement, but springs are objectionable 40 because the energy stored in the spring accelerates the forward movement of the parts and intensifies the shock when the parts are stopped in their forward position.

One object of the present invention is to 45 provide an improved buffer adapted to stop the rearward movement of the gun action without accelerating its forward movement.

A further object of the invention is to 50 provide an improved retainer or holder for a buffer of shock deadening material.

A further object of the invention is to 55 provide new and improved means for attaching a shock absorbing buffer to the frame.

With these other objects in view my invention consists of the novel combinations and arrangements of parts which are illustrated in the drawings and will be herein-after more fully described.

In the drawings:—

Fig. 1 is a fragmentary longitudinal section through a receiver of the gun of the type shown in Patent 659,507, showing my invention applied thereto. For greater clearness many details of the breech mechanism have been omitted.

Fig. 2 is a rear view of my improved shock absorbing buffer.

Fig. 3 is a section on the line 3—3 of Fig. 2.

Fig. 4 is a perspective of buffer member separate from its reinforcing member.

Fig. 5 is a front view of a modified form of my invention.

The receiver or frame 10 of the gun illustrated in the drawings is adapted to contain the barrel extension 11 and the breech block 12. Suitably supported in the breech block 12 are the firing pin 13, and the locking bolt 14, pivoted to the locking bolt operating link 15. When the gun has been fired the barrel extension and the breech block move rearwardly to the rear end of the frame. To prevent these parts striking a sharp blow on the end of the frame by means which will not accelerate their forward movement, the present invention contemplates the use of a shock preventing or buffer device which will now be described.

The shock preventing device comprises a 90 disk 16 of fiber or other suitable shock deadening, substantially non-resilient material. A portion of said disk is cut away, as seen in Figs. 2 and 4, to provide a clearance for the locking bolt and breech block operating link 15. A kerf 17 is cut about the periphery of one face of the disk. A reinforcing member in the shape of a shallow cup or container 18, preferably of metal, covers the back and edges of the buffer disk 16, and has an inturned edge 19 which overlies the kerf or recess 17. The depth of the kerf is slightly greater than the thickness of the metal of the container, whereby the face of the shock deadening disk rather than the edge 19 of the container contacts with the rear end of the breech block and barrel extension when these parts are retracted.

The metal reinforcing member thus constructed is of singular effectiveness in preventing the rapid destruction of the fiber disk by a large number of impacts of the breech block and barrel extension. If the edge of the fiber disk is left free it soon shows a tendency to separate into laminae and disintegrate, the separation beginning at the edges of the disk. By providing the metal container which firmly engages the edges of the disk this disintegration is prevented, and a shock deadener of remarkably long life is secured.

Various means may be employed for securing the fiber disk and its container in place. The securing device illustrated in the drawings comprises special screws 20 which extend thru openings in the back of the cup 18, and are received in threaded openings in the end of the frame. The heads 21 of the screws 20 occupy recesses 22 in fiber disk 16. To facilitate tightening of screws 20 in the threaded openings, each of the screws which rotates freely in its supporting recess, comprises a slot 23 in its free end, adapted to receive the bit of a screw driver inserted thru the threaded opening. An unusually convenient and effective securing device is thus provided.

In Fig. 5 I have illustrated a modification of my invention in which the inturned flange 19 terminates adjacent the sides of the operating link clearance slot, in place of surrounding said slot. Impact of the firing pin on the rim is thus prevented, and the manufacture of the device is somewhat simplified.

Other variations in the details of the structure which has been described may be resorted to, the invention being limited only by the appended claims.

I claim:

1. A shock deadening device for guns adapted to be interposed between the breech mechanism and a part of the frame in the path of movement of the breech mechanism, said device comprising a nonmetallic disk and a metallic member covering the back and edges and a peripheral section of the face of said disk but leaving a substantial part of the face exposed.

2. A shock deadening device for guns comprising a disk of an inelastic material and a reinforcing member adapted to grip

a peripheral section of said disk in a direction parallel to the axis thereof.

3. A shock deadening device for guns comprising a nonmetallic disk and a reinforcing member covering the back, edges and edge portions of the face of said disk.

4. A shock deadening device for guns comprising a disk of inelastic material having a kerf about the edge of its face, and a reinforcing member covering the back and edges of said disk, and having an inturned edge 65 edge adapted to be received in said kerf.

5. A shock deadening device for guns comprising a fiber disk having a kerf about the edge of its face, a reinforcing container for said disk covering the back and edges 70 thereof, and having an inturned edge adapted to be received in said kerf.

6. A shock deadening buffer for fire arms comprising a fiber disk having a clearance slot therein, a kerf around the edge of one 75 face of said disk, a reinforcing container for said disk covering the back and edges thereof, an edge on said container turned into said kerf, and terminating adjacent said clearance slot.

7. A shock deadening device for firearms comprising an inelastic buffer having a clearance slot therein, and a reinforcing member for said buffer adapted to grip the exterior edge of said buffer, and terminating 85 adjacent said clearance slot.

8. A shock deadening device for guns comprising a disk of inelastic material, a reinforcing member covering the back of said disk, recesses in the back of said disk, openings in said reinforcing member in alignment with said recesses, and screws having heads 90 in said recesses extending thru said openings.

9. In a firearm, in combination, a frame, threaded openings in said frame, a shock 95 absorbing buffer adapted to be secured with in said frame, and screws associated with said buffer adapted to be threaded into said openings by means of a tool inserted thru said openings.

10. In a firearm, in combination, a frame, a buffer adapted to be secured within said frame, means for securing said buffer in said frame comprising openings in said frame and securing devices attached to said buffer 105 and adapted to be secured in said openings by manipulation thereof thru said openings.

CRAWFORD C. LOOMIS.
